CLAIM

The ornamental design for a combined cosmetic tray and cartridge for a cosmetic product, as shown and described.

DESCRIPTION

FIG. 1 is a perspective view of a combined cosmetic tray and cartridges for cosmetic product showing my new design;

FIG. 2 is a top plan view thereof;

FIG. 3 is an end elevational view thereof, the side opposite being a mirror image of the side shown;

FIG. 4 is a side elevational view thereof, the side opposite being a mirror image of the side shown;

FIG. 5 is a bottom plan view thereof;

FIG. 6 is a top plan of one of the cartridge elements, shown separately for clarity of illustration;

FIG. 7 is a side elevational view thereof, the side opposite being identical to the side shown; and,

FIG. 8 is a bottom plan view thereof.

Fig. 2.

Fig. 3.

Fig. 5.

Fig. 4.
